UNITED STATES PATENT OFFICE

169,875

ELECTRIC ROASTER

Franz Wagner, Chicago, Ill., assignor to Nesco, Inc., Milwaukee, Wis., a corporation of New Jersey

Application March 4, 1953, Serial No. 23,875

Term of patent 14 years

(Cl. D81—10)

To all whom it may concern:

Be it known that I, Franz Wagner, a citizen of the United States residing at Chicago, in the county of Cook and State of Illinois, have invented a new, original, and ornamental Design for an Electric Roaster, of which the following is a specification, reference being had to the accompanying drawing, forming part hereof, and wherein

Figure 1 is a top plan view of an electric roaster embodying my new design;

Figure 2 is a front view; and
Figure 3 is a side view thereof.

I claim:
The ornamental design for an electric roaster, as shown.

FRANZ WAGNER.
